LIQUID MEASURING BOTTLE CAP AND
MASSAGE UNIT

Daniel A. Andreoli, Irvington, N. J.

Application January 24, 1950, Serial No. 140,217

2 Claims. (Cl. 128—65)

1

This invention relates to a massaging and shampooing device that is capable of serving as a closure for a container and as a measuring device for liquid in the container.

A prime object of the present invention is to provide a device of this kind that is easily attached to and detached from the neck of a bottle or other liquid container as a unit so that the device is always convenient and ready for use and cannot become misplaced.

Another object of the invention is to provide a massaging device that dispenses a measured quantity of a liquid such as a lotion or tonic on to the skin or into the hair of the user while the device is being used as a massaging device.

Another object of the invention is to provide a massaging, shampooing, liquid measuring and bottle closing means that is mounted on the bottle, removed therefrom and applied to that subject being treated as a unit.

Another object of the invention is to provide a device of this kind that is simple in construction, economical to manufacture, sanitary, leak-proof, easily manipulated and highly efficient in use.

Other objects and advantages of the invention will be apparent from the description thereof to follow taken in connection with the accompanying drawing in which:

Figure 1 is a side elevational view of a massaging and shampooing device embodying my invention shown in position on the neck of a bottle.

Figure 2 is a vertical sectional view thereof showing the valve in closed position.

Figure 3 is a view similar to Figure 2 but inverted and showing the valve open and the device filled with liquid.

Figure 4 is a vertical sectional view of the massaging and shampooing device detached from the bottle and in operative position on the skin of the user.

Figure 5 is a bottom plan view of the device.

Referring particularly to Figure 4 of the drawing, the massaging and shampooing device consists of an inverted cup-shaped member or receptacle 1 having a flat base 2 and a side wall 3 with a tapered outer surface terminating in an enlarged or thickened face or end 4. The bottom of the side wall is formed with inner shoulders 5, and the end 4 has a plurality of integral protuberances 6. On the inner surface of base 2 is an inwardly projecting integral stud forming an abutment 7.

The open end of the member 1 is closed by an

2

inverted cup-shaped insert having a bottom wall or base 8 and a side wall 9 provided with external shoulders 10 at its bottom end which are complementary to the inner shoulders 5 of the receptacle 1. The insert is formed with molded screw threads 11 on its inner surface and with a central opening 12 in its bottom wall 8. A series of discharge openings 13 is formed around the central opening.

10 The receptacle 1 is formed of hard rubber of sufficient flexibility to be forced over the insert 8 to secure the parts together. The insert is formed of plastic material of sufficient stiffness to impart the necessary rigidity to the receptacle 1 when used for massaging.

The insert extends only part way into the receptacle 1 leaving a chamber or compartment 14 between it and the receptacle for receiving a liquid having cleaning and healing properties, 15 through the openings 13 in the insert.

Passage of the liquid into and out of the compartment 14 is controlled and measured by a valve device consisting of an elongated stem 15 supporting a disc 16 at one end. The stem extends and slides through the central opening 12 in the insert with the disc 16 positioned in the compartment 14. The valve device may be of metal, plastic or other suitable material. The diameter of the disc 16 is of sufficient area to

20 overlie and cover the openings 13 in the base of the insert so that when the disc is in contact with the surface of said base, it covers said openings and provides a seal preventing the passage of liquid therethrough as shown in Figure 2.

25 The stem 15 of the valve is sufficiently long to extend slightly beyond the ends of the protuberances 6 when the valve is in closed position as shown in Figure 2.

It will be noted that the device comprises a 30 unitary structure of only three parts, to wit, the receptacle 1, the insert and the valve member, with the receptacle shaped to serve as a handle for manipulating the device.

In use, the device is mounted on a bottle 17 35 or other container for holding a cleaning and/or healing liquid by screwing the insert on to the screw threaded neck 18 thereof when the bottle is in upright position, the cooperating screw threads forming a liquid tight seal between the insert and the neck of the bottle. When in this position, the stem of the valve extends down through the neck of the bottle and the disc 16 40 is in contact with the surface of the base portion 8 of the insert thereby closing the openings 13 and sealing off the top of the bottle.

When it is desired to transfer a quantity of liquid into the compartment of the receptacle 1, the bottle 17 with the device mounted thereon is inverted to the position shown in Figure 3 whereby the valve member will fall by gravity carrying its disc 16 away from the openings 13 and uncovering the same. The opening movement of the valve is limited by the abutment 7. The liquid will fall through the openings 13 filling the compartment 14. When the compartment is filled, the bottle with the device thereon is returned to upright position when the valve will again fall by gravity carrying its disc 16 into contact with the surface of the base 8 of the insert again sealing the openings 13 and trapping a quantity of liquid in the compartment 14. The device is then unscrewed from the neck of the bottle with the liquid in the compartment and with the lower end of the stem 15 of the valve protruding beyond the ends of projections 6 ready for massaging and shampooing. The device is placed on the scalp or other part of the skin indicated diagrammatically at 19 (Figure 4) needing attention and downward pressure exerted thereupon whereby the stem 15 of the valve will be forced inwardly moving the disc 16 off its seat on the base 8 of the insert to permit a measured quantity of the liquid to flow on to the part of the body being treated. At the same time, a rubbing or massaging pressure is exerted on the protuberances 6 whereby the liquid is rubbed into the scalp or skin being treated to the massaging action.

When the massaging and shampooing action has been completed, the device as a unit is screwed back on to the neck of the bottle out of the way of any harm or injury and ready and convenient for a repeat performance.

Changes in details of construction might be made without departing from the principle of the invention.

What I claim is:

1. A device of the kind described comprising a

liquid receptacle having an opening in one end with massaging protuberances on the face of said end surrounding said opening, an insert closing said open end, said insert having a discharge opening for the liquid in the receptacle, and a gravity actuated valve to close said opening when said end is facing downwardly and to open said opening when said receptacle is inverted, said parts forming a unitary structure, said insert having means for detachably securing the unit to the externally screw threaded neck of a liquid container.

2. A massaging and shampooing device comprising a receptacle having a recess in one end and massaging protuberances on the face of said end surrounding said recess, the base of said recess having a discharge opening for the liquid in the receptacle, and a gravity-actuated valve to close said opening when said end of the receptacle is facing downwardly and to open said opening when the receptacle is inverted, said valve having a portion extending beyond the plane of said end face when the valve is in position to close said discharge opening so that said valve will be automatically opened by contact with a surface upon pressure of said end face against said surface, said recess having internal fastening elements for cooperation with complementary fastening elements on a bottle for liquid for separably attaching said receptacle to said bottle.
